UNITED STATES PATENT OFFICE.

PIERRE B. NOYES, OF NIAGARA FALLS, NEW YORK, ASSIGNOR TO THE ONEIDA COMMUNITY, LIMITED, OF KENWOOD, NEW YORK.

DESIGN FOR A SPOON, &c.

SPECIFICATION forming part of Design No. 25,558, dated June 2, 1896.

Application filed April 25, 1896. Serial No. 589,130. Term of patent 3½ years.

To all whom it may concern:

Be it known that I, PIERRE B. NOYES, a citizen of the United States, residing at Niagara Falls, in the county of Niagara and State of New York, have invented and produced a new and original Design for Spoon and Fork Handles, of which the following is a specification, reference being had to the accompanying drawing, showing a part thereof.

10 This design relates to the ornamentation of spoon and fork handles, and the accompanying drawing represents a face view of a spoon embodying the design.

15 The leading feature of my design consists of a plain field arranged upon the outer enlargement of the handle and flanked by a pair of scrolls and foliated scrolls arranged upon the inner or small bulge of the handle.

20 The handle has the configuration commonly known as the "fiddle outline." Upon its outer enlargement or bulge is a plain field *b*, inclosed by foliated scrolls or ornamentations

c, which follow the outline of the adjacent portion of the handle, and upon the tapering end portion of the handle, above these scrolls, 25 is a leaf-like ornament *d*. The inner or less-pronounced bulge of the handle is covered with a foliated C-shaped scroll *f*, and below the latter are smaller scroll-like ornaments *g*.

Upon the extreme inner portion of the shank 30 is a scroll-ornament *h*, and between the latter and the ornaments *g* the shank is plain.

My design may obviously be applied to the handle of a fork, as well as to a spoon-handle.

What I claim is—

35 The design for the handle of a spoon or fork substantially as herein shown and described.

Witness my hand this 21st day of April, 1896.

PIERRE B. NOYES.
